UNITED STATES PATENT OFFICE

127,178

DESIGN FOR A FISH LURE

Carl H. Weidenmier, Berlin Center, Ohio

Application January 27, 1940, Serial No. 89,797

Term of patent 14 years

To all whom it may concern:

Be it known that I, Carl H. Weidenmier, a citizen of the United States and a resident of Berlin Center, county of Mahoning, and State of Ohio, have invented a new, original, and ornamental Design for a Fish Lure, of which the following is a specification, reference being had to the accompanying drawing, forming a part thereof.

In said drawing:

Fig. 1 is a side elevation;
Fig. 2 is a front elevation; and
Fig. 3 is a rear elevation of a fish lure showing my new design. The drawing is shaded to represent contrasting color.

I claim:

The ornamental design for a fish lure, as shown and described.

CARL H. WEIDENMIER.
